FUEL BURNER

Frank T. Cope, Salem, Ohio, assignor to The
Electric Furnace Company, Salem, Ohio, a cor-
poration of Ohio

Application June 9, 1938, Serial No. 212,764

7 Claims. (Cl. 158—99)

The invention relates to fuel burners and more particularly to a burner for discharging a premixed mixture of fuel and air into and burning the same in a heating or heat treating furnace.

In certain types of heating and heat treating furnaces, it has been found desirable if not necessary to use burners which burn a premixed mixture of gas and air supplied to all the furnace burners from a manifold or manifolds, into which manifold or manifolds the gas-air mixture in the desired proportions is introduced. This involves certain hazards because the premixed gas-air mixture delivered to the manifold or manifolds and thence to the burners, is explosive in character and the individual burners must be so constructed and operated that explosions due to "flash-back" will not occur.

On the other hand, modern heat treating furnace design requires a flexibility of operation for any given furnace installation in order that the same may be used for either high or low temperature work during either long or short material heating cycles. This necessitates a fuel burner construction which has a high turn-down capacity for burning say as much as twenty or more times as much fuel at high flow or pressure as is burned at low flow or pressure. Such a burner would be termed as having a 20 to 1 turn-down ratio or capacity.

Any given mixture of gas or fuel and air has a certain velocity of flame propagation and when the mixture is burned from a burner nozzle, if that velocity is exceeded by a certain amount, at high pressures and rates of flow, the flame leaves the nozzle and blows out. If the velocity is diminished below a certain amount, at low pressures or low rates of flow, the flame may flash back into the supply conduit.

Pre-mix burners have been used including a nozzle having a large central hole through which the fuel-air mixture is discharged into a refractory burner tunnel, but such burners have a turn-down ratio of only about 4 to 1 and will blow-off at a pressure of about 10 inches of water.

Pre-mix burners have also been used, which include a nozzle having a multiplicity of small holes therethrough parallel to the center line of the burner and which are particularly adapted for low pressures or low rates of flow, but only have a turn-down ratio of about 6 to 1.

The single hole pre-mix burner has been modified to increase its turn-down ratio and also to raise the blow-off point by providing a flame retention tip which includes a plurality of small holes discharging from the burner around the

central aperture, several designs of the same being available. However, these types of burners only have a turn-down ratio of about 7 to 1.

The figures given with relation to the turn-down ratio of prior art burners are average and approximate as they are subject to variation depending upon the size and exact proportions of the burners and upon furnace operating conditions such as furnace temperature. The ratios may be improved somewhat if great care is used in burner design and operation; but such improvement does not render the prior art burners adequate where a large turn-down ratio is essential.

Thus, the various known types of pre-mix burners, some of which are satisfactory for low pressure work and others for high pressure work, at the most only have a turn-down ratio of approximately 7 to 1 and are wholly inadequate or unsuitable for operation where a burner having a turn-down ratio of 20 to 25 to 1 is required.

These circumstances have accordingly necessitated materially increased installation and operating costs for providing additional burners for high or fast heating and for providing for cutting out some of the burners for low or slow heating in any given furnace installation where flexibility of operation is desired or necessary.

Accordingly, it is a general object of the present invention to provide a pre-mix fuel-air burner which has a turn-down ratio of the order of 20 or more to 1.

It is a further object of the present invention to provide a pre-mix fuel-air burner which not only has a large turn-down ratio, but which will operate satisfactorily at high pressures without blowing off, and which will operate satisfactorily at low pressures without flashing back.

Moreover, it is an object of the present invention to provide an improved pilot construction for a fuel burner, which is especially adapted for use with a burner having a high turn-down ratio.

Moreover, it is an object of the present invention to provide a pre-mix fuel-air burner construction which tends to eliminate the causes of flash-back or back firing.

Likewise, it is an object of the present invention to provide a pre-mix fuel-air burner construction which tends to eliminate the causes of blowing off.

And finally, it is an object of the present invention to generally improve the construction and operation of pre-mix fuel-air burners and pilots, and to generally increase the flexibility of oper-

ation of fuel-air fired heating and heat treating furnaces.

These and other objects may be obtained by the elements, parts, combinations, arrangements and constructions constituting the present invention, a preferred embodiment of which is shown in the accompanying drawing and is hereinafter described in detail and claimed, and which may be stated in general terms as including in combination, a furnace wall having an opening therein, a burner housing mounted in said wall opening, a preferably refractory burner tunnel block having a flaring preferably conical opening therethrough mounted in said wall opening and burner housing, a burner nozzle mounted in said housing and tunnel block having a chamber therein connected with a conduit for supplying a fuel-air mixture thereto and having a plurality of nozzle holes communicating between the chamber and said tunnel block opening, the axes of all of said holes being angled so as to intersect the conical tunnel wall and being all formed preferably as elements of a cone, a pilot for said burner releasably mounted on said burner housing including a tip, and a preferably curved passage formed in the tunnel block communicating with said pilot tip and with said tunnel block opening, the place of communication of said passage with said tunnel block opening preferably being in or adjacent to the circumferential zone or region where the axes of the burner nozzle holes intersect the conical tunnel block opening wall.

In the drawing.

Figure 1 is a fragmentary sectional view taken 35 as on the line 1—1, Fig. 2, illustrating the improved fuel burner construction in the wall of a heating or heat treating furnace;

Fig. 2 is an elevation of certain of the parts shown in Fig. 1;

Fig. 3 is an enlarged fragmentary sectional view of parts of the burner nozzle and burner tunnel block shown in Fig. 1; and

Fig. 4 is a sectional view on line 4—4 of the burner nozzle looking in the direction of the 45 arrows, Fig. 3.

Similar numerals refer to similar parts throughout the various figures of the drawing.

The improved burner is shown in Fig. 1 wherein a wall of a heating or heat treating furnace is indicated generally at 5, and the same is provided with a preferably square or rectangular opening 6 terminating on the inside in a flaring mouth 7, which opens into the heating chamber located at the left hand of the wall 5.

The improved burner is composed generally of three parts, a housing 8, a tunnel block 9 and a nozzle 10. The housing 8 is preferably a casting and includes tubular preferably rectangular side walls 11 extending into the furnace wall opening 6, an outer end flange 12 provided with suitable means indicated at 13 for securing the housing member 8 to the furnace wall, and an inner partition wall 14 located intermediate the ends of the housing member tubular walls 11. The partition wall 14 is provided with a central preferably round opening 15.

The tunnel block 9 is preferably a refractory block preferably having outer rectangular or square surfaces 16 fitting within and cemented to the walls forming the furnace opening 6, said walls 16 also fitting at 17 within the tubular housing walls 11, with the outer end of the refractory block 9 abutting at 18 against the housing partition wall 14.

A central opening is provided in the block 9 including a preferably cylindrical opening portion 19 formed in the tunnel block 9 aligned with the partition wall opening 15 and the opening portion 19 extends for a short distance from the partition wall 14 to a region indicated at 20. The central opening in the burner tunnel block 9 then begins to flare or enlarge in cross section as the furnace end of the tunnel block is approached to form an expanding opening portion having flared walls indicated at 21. The flared wall 21 of the tunnel block opening is preferably formed as a conical surface, any element of which preferably makes an angle of approximately 8 degrees with the center line or axis of the tunnel block 9, tapering from the end 20 of the cylindrical opening portion to the furnace end 22 of the tunnel block 9.

The nozzle 10 is preferably a casting having a cylindrical wall 23 terminating at one end in an outturned flange 24 secured by suitable bolts 24' to housing 8, with the wall 23 cemented and sealed in the housing opening 15 and tunnel block cylindrical opening portion 19. The inner end of the tubular nozzle is provided with a heavy metal end wall 25 forming a compartment 26 within the nozzle, to which compartment a fuel-air mixture is supplied from a conduit 27 threaded into nozzle 10 at 28. The other end of conduit 27 may be provided with a T 29. A nipple 30 connected to the other end of the T 29 and capped at 31 with a sight glass, provides for ready cleaning and inspection of the nozzle 10.

A conduit 32 leads from the T 29 through a fire check 33, a union 34, a valve 35 and pipe 36 to a manifold, from which the proper or desired fuel-air mixture is supplied to the burner nozzle 10.

The inner end wall 25 of nozzle 10 is provided with a series of small holes 37, which form the only communication between the nozzle chamber 26 and the flared tunnel block opening 21. The axes of holes 37 all diverge from the center or axis of the burner nozzle 10 on a greater taper than the taper of the wall 21 of the burner tunnel opening; so that the axes of all of the holes 37, indicated by dot-dash lines at 38, intersect the diverging tunnel wall 21 at 39.

The axes of holes 37 are preferably formed as elements of a cone, preferably on about a 15 degree angle. The angle of divergence of the tunnel opening wall 21 and the angle of divergence of the axes of holes 37 may of course vary somewhat from the particular figures given so long as the angle of divergence of the nozzle holes is substantially greater than the angle of divergence of the tunnel opening so that the axes of the holes intersect the tapered tunnel opening surface intermediate the ends thereof.

A pilot 40 is flexibly removably and alignably mounted by a spring device 41 with its tip 42 communicating through opening 43 in burner block partition wall 14 with a passage 44, and the pilot 40 is preferably parallel with and closely adjacent to the nozzle 10. The passage 44 is preferably curved from opening 43 to a place of communication 45 with diverging tunnel opening 21. The place of communication 45 is preferably quite close to burner nozzle 10 and in or adjacent to the annular zone 39 where the axes of the nozzles 37 intersect the wall of diverging tunnel opening 21 for reasons to be later described.

Passage 44 is shown as being curved, which shape is preferable for smoothness of flow, but it is understood that the same may be straight

from opening 43 to zone or region 45. The place of intersection 45 between passage 44 and diverging tunnel opening 21 should be closer to nozzle 10 than to the furnace end of tunnel block 22, because it is important to reduce the length of the passage 44 as much as possible and also to bring the pilot flame close to the burner nozzle.

The pilot 40 may communicate through flexible conduit 46 with any suitable source of fuel. The particular pilot construction assembly and mounting shown but not claimed herein, is claimed in my copending application filed of even date herewith, Serial No. 212,765.

In operation, a premixed fuel-air mixture, preferably a mixture of natural or artificial gas and air, is supplied from the manifold to the burner nozzle 10 and this mixture is discharged from the nozzle chamber 26 through the diverging holes 37 to impinge against the sides of the diverging tunnel opening 21. Combustion takes place at the point where the velocity of the fuel-air mixture is slow enough somewhere within the diverging tunnel opening 21; and when the burner tunnel block is heated up, the flame begins in the vicinity of the zone 39 where the mixture streams impinge against the diverging tunnel opening wall 21.

Tests performed on a burner threaded for a 1" pipe having a 1½" outside diameter and having ten $\frac{1}{8}$ " diameter holes on a 1¼" circle at the external face, each at a 15° angle, such as shown in the accompanying drawing, indicate, when operating with a fuel-air mixture under high pressure and flow, that the burner does not blow off until a pressure of 5¼ inches of mercury is reached with a cold tunnel block 9, or 6 inches of mercury with a hot tunnel block 9. The burner burned in an exceedingly satisfactory and efficient manner with a pressure of 5 inches of mercury and a flow of 3240 C. F. H. of a premixed natural gas and air mixture calculated to support perfect combustion. With the same mixture, the burner was throttled down to a flow of 20 C. F. H. with a cold tunnel block 9 and 32 C. F. H. with a hot tunnel block 9 without going out or flashing back.

These conditions indicate a turn-down ratio of 3240/20 or 162 to 1; however, if a minimum flow were taken at 40 C. F. H. the turn-down ratio would be 81 to 1.

It is to be understood that the above tests were made under more or less ideal laboratory conditions, but they show that in practical or commercial operation, the burner may be rated as having a turn-down ratio far in excess of say 20 to 1, which is a turn-down ratio heretofore desired but never obtained by any pre-mix fuel burner known to me.

It is believed that back-firing in a pre-mix burner is stimulated at low flows or pressures by the presence of a large nozzle opening or openings, and the improved burner nozzle avoids the causes of back-firing under any desired low operating pressures or flows by only utilizing small nozzle openings extending a considerable distance through a heavy metal wall. Thus, by breaking up the flow of premixed fuel and air into a large number of small streams and by the cooling effect of the heavy metal wall 25 through which the nozzle holes 37 pass, the improved burner does not flash-back at extremely low pressures and flows.

While the principles of surface combustion are known, the same have never to my knowledge been incorporated in a pre-mix burner having a

high turn-down ratio. This principle is incorporated in the present burner by directing the angular or divergent holes 37 against the wall 21 of the expanding or diverging burner tunnel opening. Thus the velocity of the premixed gas and air streams is slowed down and the premixed gas and air streams are impinged against the tunnel wall, so that combustion takes place at and adjacent to and with in the surfaces of the diverging tunnel opening 21.

This is evidenced by a red or white hot ring around the tunnel opening after the same has become heated, generally in the region 39 of intersection of the axes of holes 37 with diverging surface 21; and this red or white hot tunnel surface tends further to promote combustion and to keep the burner lighted even at low pressures and flows.

As previously stated, it is desirable to locate the end 45 of pilot passage 44 somewhere adjacent to the region which becomes red or white hot when the burner is burning so as to provide additional means for keeping the burner lighted at either low or high flows.

As has been described above, the particular pilot passage arrangement and location is especially advantageous in connection with the particular burner nozzle shown and claimed herein, yet the particular pilot passage arrangement is equally useful in connection with other types and kinds of fuel burners.

Accordingly, the present improvements provide a pre-mix burner construction which avoids the difficulties present in prior structures, which has a turn-down ratio of the order of 20 or more to 1, which operates satisfactorily at high pressures without blowing off and at low pressures without flashing back, which tends to eliminate the causes of flashing back and blowing off, which incorporates an improved pilot construction, and which generally increases the flexibility of operation of fuel-air fired heating and heat treating furnaces.

Moreover, the sealed in pre-mix burner nozzle construction is especially adapted for certain types of special atmosphere furnace work and the improved construction lends further flexibility of operation to such furnaces.

Having now described the features of the invention, the construction, operation and use of a preferred embodiment thereof, and the advantageous, extraordinary and heretofore unattainable results attained by the improved constructions; the new and useful parts, elements, combinations, constructions and devices, and reasonable mechanical equivalents thereof obvious to those skilled in the art, are set forth in the appended claims.

I claim:

60 1. In a pre-mix fuel-air burner, a burner block having walls forming a through opening having an inner tubular surface, a burner nozzle sealed in said opening closing one end thereof, said nozzle being provided with a plurality of holes forming the sole communication between the nozzle and burner block opening, and the axes of said holes being elements of a cone and intersecting said tubular burner block surface.

65 2. In a pre-mix fuel-air burner, a burner block having walls forming a through opening, a burner nozzle sealed in said opening closing one end thereof, the opening having a portion flaring conically from the nozzle end to the other end thereof, said nozzle being provided with a plurality of holes forming the sole communication between

the nozzle and flaring opening portion, the axes of said holes being elements of a cone diverging in the same direction as the flaring conical opening, and the angle of divergence of the hole axes cone being greater than that of the flaring opening cone.

3. In a pre-mix fuel-air burner, a burner block having walls forming an opening therethrough, a burner nozzle sealed in said opening closing one end thereof, the opening having a portion flaring from the nozzle to the other end formed as a surface of a frustum of a cone, said nozzle being provided with a plurality of holes forming the sole communication between the nozzle and flaring opening portion, the axes of said holes being elements of a cone coaxial with and diverging in the same direction as the flaring opening conical frustum, and the angle of divergence of the hole axes cone being greater than that of the flaring opening conical frustum.

4. In a pre-mix fuel-air burner, a refractory burner block provided with a through opening, a burner nozzle member sealed in said opening having side and end walls forming a compartment, a conduit connected with said compartment for supplying a fuel-air mixture thereto, said nozzle end wall being provided with a plurality of holes communicating between the compartment and burner block opening, said burner block opening having walls flared from the nozzle to the other end thereof, and the axes of said holes being elements of a cone and intersecting the flaring burner block wall.

5. In a pre-mix fuel-air burner, a burner housing, a burner block mounted in said housing, a burner nozzle mounted in said burner block and burner housing, and a pilot mounted on said burner housing, the burner block being provided with a combustion tunnel flaring from said nozzle, said nozzle being provided with a plurality

of holes providing the sole communication between the nozzle and combustion tunnel, the axis of each hole intersecting the flaring tunnel wall whereby the points of intersection lie in an annular zone intermediate the ends of the flaring tunnel, and said burner block being provided with a passage communicating with the pilot and communicating with the combustion tunnel adjacent to said zone.

10 6. In a pre-mix fuel-air burner, a burner housing, a burner block mounted in said housing, a burner nozzle mounted in said burner block and burner housing, and a pilot mounted on said burner housing, the burner block being provided with a combustion tunnel flaring from said nozzle, said nozzle being provided with a plurality of holes providing the sole communication between the nozzle and combustion tunnel, the axis of each hole intersecting the flaring tunnel wall 15 whereby the points of intersection lie in an annular zone intermediate the ends of the flaring tunnel, and said burner block being provided with a curved passage communicating with the pilot and communicating with the combustion tunnel adjacent to said zone.

20 7. In a pre-mix fuel-air burner, a burner block having walls forming a tubular combustion tunnel extending from the outer end to the inner end of said block, a burner nozzle at the outer end of said tunnel, said nozzle being provided with a plurality of holes communicating between the nozzle and combustion tunnel, the axes of said holes being elements of a cone and intersecting said combustion tunnel in an annular zone 25 intermediate the ends thereof, said burner block being provided with a curved passage extending inward from the outer end of the block and intersecting the combustion tunnel adjacent to said zone, and a pilot firing into said curved passage.

FRANK T. COPE.
